(57) **CLAIM**

The ornamental design for a headwear with nose and mouth windows, as shown and described.

DESCRIPTION

FIG. 1 provides a first perspective view of a headwear with nose and mouth windows, with closures in a closed position. FIG. 2 provides a second perspective view of the headwear of FIG. 1, with closures in the closed position.

FIG. 3 provides a front view of the headwear of FIG. 1, with closures in the closed position.

FIG. 4 provides a back view of the headwear of FIG. 1.

FIG. 5 provides a first side of the headwear of FIG. 1, with closures in the closed position.

FIG. 6 provides a second side view side of the headwear of FIG. 1, with closures in the closed position; and,

FIG. 7 provides a front view of the headwear of FIG. 1, with closures in the opened position.

The broken lines illustrate portions of the article that form no part of the claimed design.

1 Claim, 7 Drawing Sheets
